(57) **CLAIM**

The ornamental design for a packaging assembly, as shown and described.

DESCRIPTION

FIG. 1 is a perspective view of a packaging assembly in accordance with the present invention. The packaging assembly is shown with the lid in an open position; an electronic cigarette case is shown in broken lines within the packaging assembly and forms no part of the claimed design;

FIG. 2 is a front view of the packaging assembly of FIG. 1, shown with the lid in an open position;

FIG. 3 is a rear view of the packaging assembly of FIG. 1, shown with the lid in an open position;

FIG. 4 is a top view of the packaging assembly of FIG. 1;

FIG. 5 is a bottom view of the packaging assembly of FIG. 1;

FIG. 6 is a left side view of the packaging assembly of FIG. 1, shown with the lid in an open position;

FIG. 7 is a right side view of the packaging assembly of FIG. 1, shown with the lid in an open position;

FIG. 8 is a perspective view of a packaging assembly in accordance with the present invention, shown with the lid in a closed position;

FIG. 9 is a front view of the packaging assembly of FIG. 8, shown with the lid in a closed position;

FIG. 10 is a rear view of the packaging assembly of FIG. 8, shown with the lid in a closed position;

FIG. 11 is a top view of the packaging assembly of FIG. 8;

FIG. 12 is a bottom view of the packaging assembly of FIG. 8; and

FIG. 13 is a left side view of the packaging assembly of FIG. 8, shown with the lid in a closed position; and,

FIG. 14 is a right side view of the packaging assembly of FIG. 8, shown with the lid in a closed position.
